(57) **CLAIM**

The ornamental design for an animal trap, as shown and described.

DESCRIPTION

FIG. 1 is a perspective view of an animal trap showing one embodiment of the new design;

FIG. 2 is a rear view of the animal trap of FIG. 1;

FIG. 3 is a front view of the animal trap of FIG. 1;

FIG. 4 is a right side elevation view of the animal trap of FIG. 1;

FIG. 5 is a left side elevation view of the animal trap of FIG. 1;

FIG. 6 is a top plan view of the animal trap of FIG. 1;

FIG. 7 is a perspective view of an animal trap showing a second embodiment of the new design;

FIG. 8 is a rear view of the animal trap of FIG. 7;

FIG. 9 is a front view of the animal trap of FIG. 7;

FIG. 10 is a right side elevation view of the animal trap of FIG. 7;

FIG. 11 is a left side elevation view of the animal trap of FIG. 7;

FIG. 12 is a top plan view of the animal trap of FIG. 7;

FIG. 13 is a perspective view of an animal trap showing a third embodiment of the new design;

FIG. 14 is a rear view of the animal trap of FIG. 13;

FIG. 15 is a front view of the animal trap of FIG. 13;

FIG. 16 is a right side elevation view of the animal trap of FIG. 13;

FIG. 17 is a left side elevation view of the animal trap of FIG. 13; and

FIG. 18 is a top plan view of the animal trap of FIG. 13;

FIG. 19 is a perspective view of an animal trap showing a fourth embodiment of the new design;

FIG. 20 is a rear view of the animal trap of FIG. 19;

FIG. 21 is a front view of the animal trap of FIG. 19;

FIG. 22 is a right side elevation view of the animal trap of FIG. 19;

FIG. 23 is a left side elevation view of the animal trap of FIG. 19; and,

FIG. 24 is a top plan view of the animal trap of FIG. 19.

The broken lines contained in any of the drawings form no part of the claimed design.
